FURNITURE SEAT CONSTRUCTION

Murray Weingarten, New York, N. Y.

Application October 11, 1943, Serial No. 505,722

10 Claims. (Cl. 155—179)

1

This invention relates generally to furniture construction and more particularly to the support for the seating platform and/or the back of chairs, sofas, divans, and similar articles of furniture.

It is one of the principal objects of the present invention to provide upholstered furniture construction in which the spring supporting platform, or webbing layer is resiliently supported in position so that the normal spring base of the cushion supporting springs is maintained substantially constant throughout the useful life of the upholstered article.

An advantage of the present construction lies in the fact that the novel support units require no special mounting brackets and, in fact, may be installed upon the furniture frame to coact with the other parts of the article of furniture by an ordinary workman who requires only ordinary upholsterer's tools and equipment to complete the operation.

A feature of the present invention lies in the fact that the workman assembling the article of furniture may, by varying the tension and/or position of certain of the parts of the support unit, control the spring action so as to produce an upholstered or padded article of furniture having varying degrees of resiliency characteristics.

For the purpose of describing my invention and pointing out the novelty thereof I have shown, by way of illustration, the incorporation of the resilient support units in a chair. As will be obvious to those skilled in the art to which the present invention relates, this same structure can, of course, be incorporated in all manner of articles of furniture in which a padded or upholstered or other comfort providing surface or platform is used, as for example in springs for beds, spring filled mattresses, chairs, divans, studio couches, or the upholstered furniture upon various vehicles, such as trains, aeroplanes and automobiles.

These objects and other incidental ends and advantages will more fully appear in the progress of this disclosure and be pointed out in the appended claims.

In the drawings in which similar reference characters designate corresponding parts throughout the several views:

Figure 1 is a plan view as seen from the plane 1—1 on Figure 2 showing a preferred embodiment of the invention.

Figure 2 is a vertical sectional view of an article of furniture embodying the invention, as might

2

be seen from a plane 2—2 on Figure 1 with the addition of the overlying parts.

Figure 3 is a fragmentary enlarged detail plan view showing one of the ends of the support elements shown in the left portion of Figure 1.

Figure 4 is a fragmentary enlarged detail vertical section view as seen from the plane 2—2 on Figure 1 or the left hand lower portion of Figure 2.

Figure 5 is a fragmentary enlarged sectional view as seen from the plane 5—5 on Figure 4.

Figure 6 is a fragmentary enlarged detailed sectional view as seen from the plane 6—6 on Figure 3.

Figure 7 is a view in perspective showing one of the combination slider and strain distributing members prior to installation.

Figure 8 is a fragmentary side elevational view corresponding to Figure 4 but showing a second embodiment of the invention.

Figure 9 is an elevational view partly in section as seen from the plane 9—9 on Figure 8.

In accordance with the invention the upholstered article of furniture is generally indicated by reference character 10 and as previously described, may be an upholstered chair. As seen in Figure 2 the chair frame 11 may be of the usual construction including front legs 12 and rear legs 13. Disposed above the legs 12 and 13 are the

seat front frame element 14, seat rear frame element 15, and seat side frame elements 16 and 17. Suitably secured to the under surfaces of the frame elements 14—17, inclusive, in any suitable manner as for example by the use of upholsterer's tacks (not shown) is a platform base 18. The base 18 may be composed of any suitable material which is flexible and stretchable. The base 18 may be composed of a single sheet of webbing as shown or the same may be composed

of interwoven webbing. Such bases as just described are well known in the art and do not require further description. They are subject to undesirable stretching when in use and as will appear more fully hereinafter, this disadvantage is avoided by the present novel construction.

Disposed above the base 18 are a plurality of resilient elements 19. The resilient elements 19 may be of any suitable number determined by the type of action required in the chair as completed.

By way of example, I have shown the chair as including six of these resilient elements 19, positioned as shown in Figure 1. Where desired, these elements may be increased or decreased in number and rearranged in position upon the base 18 to suit the requirements of the particular

chair. Disposed above the resilient elements 19 is a covering element 20. The covering element 20 serves to distribute the stress transmitted to the resilient elements 19, to restrict dust from entering within the chamber formed by the base 18, the covering element 20 and the surrounding portions of the frame 11. The covering element 20 may be composed of muslin or similar material and may be secured in any suitable manner as for example by the use of upholsterer's tacks (not shown) to the upper surfaces of the frame elements 14-17, inclusive. In Figure 1 the covering element 20 has been removed for the purpose of showing the construction of the parts beneath.

Superposing the covering element 20 is the cushioning element 21 which may be of any suitable construction, as for example, a filling of curled hair, moss, cotton, or kapok. The cushioning element 21 may be covered with any desired upholstery material which forms the seat surface 22.

The base 18 is provided with a plurality of base support units generally indicated by numeral 23. Thus as seen in Figure 1 the base support units are three in number and for the purpose of avoiding needless repetition since all of these units are substantially identical, a detailed description of one will be given, which will suffice for all. As seen in Figure 2 the base support unit 23 includes a body in the form of an elongated strap element 24. This strap element may be made of any suitable flexible material and while the same may have stretchability of low order it is preferable that the same be substantially non-extensive in length. I have found that of the suitable materials of which the elongated strap element 24 may be constructed, woven cotton webbing is satisfactory. Obviously, other materials having similar characteristics may be substituted. The front and rear ends of the elongated strap element 24 generally indicated by numerals 25 and 26, respectively, are substantially identical and a detailed description of the front end as seen in Figures 3-6, inclusive, will serve as a description of the rear end 26 as well. As best seen in Figure 4, the front terminal 27 is folded upon itself to form a closed loop or bight or spring enclosing portion 28 and is suitably connected to the portion 29 of the body 24 in any suitable manner, as for example by the stitching 30. Other methods of connection of the terminal 27 to the portion 29 which I have found satisfactory are riveting, interweaving, splicing or securing by means of adhesive. The bight 28 at the outer extremity thereof thus forms a fold or bend 31 which is provided with a pair of orifices 32 and 33. These orifices are provided with reinforcements 34 and 35. The reinforcements 34 and 35 may be composed of metal eyelets installed in a well known manner, or may be composed of plastic eyelets molded into place.

Disposed within the spring enclosing portion 28 is a helical spring 36 which is of such construction that in a condition of equilibrium substantial spaces exist between the convolutions thereof. In the normal operation of the present invention the spring 36 is subjected to compression and as is best seen in Figure 5 the spring 36 which is generally elongated is bent upon itself into a substantially U-shape. And the ends 37 and 38, that is to say, the terminal convolutions of the spring 36 are provided with pressure distributing members 39 and 40 which may take the form of flanged bushings in which the body

portion of the bushing is engaged between the terminal and adjacent convolutions of the spring 36 while the flange portions are disposed between the terminal convolutions of the spring 36 and the inner surfaces of the reinforcements 34 and 35. Passing through the reinforcements 34 and 35 and the pressure distributing members 39 and 40 is a flexible frame attaching element 41. The outer portions of the element 41 adjacent the ends 42 and 43 are interconnected by a connector 44. The ends 42 and 43 are then secured to the upper surface of the particular frame portion of the frame 11 by winding said ends about upholsterer's tacks 45, 46, 47 and 48. This construction is seen in Figure 3 wherein the tacks 45-48, inclusive, have been driven into the top surface 49 of the seat front frame element 14. The body or elongated strap element 24 has the central portion thereof disposed below the platform base 18 and said element 24 penetrates a pair of orifices 50 and 51 in the platform base 18. During the operation of the invention, as will more fully appear hereinbelow, the portions of the strap element 24 which pass through the orifices 50 and 51 are subject to movement through said orifices. Furthermore, a considerable portion of the weight placed upon the cushioning element 21 by the sitter is concentrated in effect along the inner opposed edges of the orifices 50 and 51. The combination slider and strain distributing members 52 and 53 are provided to protect the borders of the orifices 50 and 51 and to distribute said weight over a greater area. This construction provides smoother and more responsive action of the structure and also adds to the durability thereof. In Figure 7 the combination slider and strain distributing member 52 is shown prior to the connection thereof with the platform base 18. The member 52 has a rounded body portion 54 and a plurality of prongs 55. The installation of the members 52 and 53 is a relatively simple matter in that the prongs 55 are pushed through the base 18 wherein they make their own orifices for penetration and the prongs 55 are struck over or swaged to take the position shown in Figure 6.

By way of example one method of assembling the construction in the article 10 is here given. The base 18 may be cut to size so as to be coterminous with the outer horizontal edges of the frame 11 at the seat portion thereof. Depending upon the number of the elements 23 which it is proposed to utilize in the chair, the base 18 may now be provided with pairs of opposed orifices corresponding with the orifices 50 and 51. The members 52 and 53 and others corresponding thereto are secured in position next to the orifices corresponding to the orifices 50 and 51.

Next the resilient elements 19 are positioned and secured to the upper surface of the base 18 in any usual manner as by clinching, stapling, or stitching.

Following this the units 23 are next inserted in such manner through the orifices 50 and 51 and the other orifices corresponding thereto with the bight or spring covering portions corresponding to the portions 28 taking the general position indicated in Figure 4. Following this the ends 70 corresponding to the ends 42 and 43 of the flexible frame attaching element 41 are secured to the frames nearest thereto by winding the ends about the tacks which are then driven tightly into the frame. At this time the springs corresponding to the spring 36 are placed under a certain

amount of tension depending upon the resiliency characteristics which it is desired the finished chair or other upholstered article shall have.

Now the covering element 20 and the cushioning element 21 and the seat surface 22 may be put in place in a well known manner.

The back portion generally indicated by reference character 56 of the article 10 may be constructed generally similarly to the seat portion 57. Thus the lower and upper frame elements 64 and 65 are maintained in position between vertical frame elements, only one of which, namely the vertical frame element 66, is seen in the drawings. Secured to the rear surfaces of the frame elements 64, 65 and 66 in any suitable manner, as for example, by the use of upholsterer's tacks (not shown) is a back base 68, which may be similar to the base 18. Forwardly of the base 68 are a plurality of resilient elements 69 which are similar to the elements 19. Forwardly of the elements 69 is a back covering element 70.

Superposing the covering element 70 is a cushioning element 71 which may be covered with any desired upholstery material, which forms the front surface 72 of the chair back.

The back base 68 is provided with a plurality of back base support units generally indicated by numeral 73 which may be of any suitable number. Each one of the support units 73 is substantially identical with the support units 23 previously described, with the exception that they may be composed of lighter weight material and the helical springs therewithin corresponding to the springs 36 may have a softer action. This may be accomplished, for example, by fabricating the springs within the units 73 of lighter gauge wire.

In all principal respects the installation of the parts just described on the back portion 56 of the chair 10 may be accomplished in a manner similar to that previously described in connection with the parts as installed to form the seat portion 57 of the chair 10.

It may thus be seen that when the chair 10 is occupied by a sitter downward pressure caused by the weight of the sitter upon the seat portion 57 of the chair will cause a compression of the cushioning element 21. In addition to the last described compression, there will be a transmission of movement to the covering element 20 which in turn distributes the weight over a plurality of the resilient elements 19. The elements 19 will be compressed to a certain degree and will in addition transmit movement to the base 18 causing the same to become lowered in position. This lowering of the base 18, however, is controlled by the units 23. As the base 18 at the central portion thereof becomes lowered it contacts the body 24 of the unit 23 and this downward movement is transmitted to the ends 25 and 26 of the unit 23. Because the flexible frame attaching elements 41 are positively secured at the outer ends thereof to the stationary frame adjacent thereto downward movement of the body 24 will cause a compression of the springs 36. Thus the springs 36 supplement the action of the resilient elements 19 and resiliently support the base 18 and prevent the same from permanently sagging. As previously mentioned the base 18 has a certain limited resiliency and therefore when the chair 10 is sat upon distortion will take place in the base 18 owing to the gravity forces which have been transmitted thereto. Movement of the base 18 with relation to the body 24 may readily occur by reason of the reduced frictional asso-

ciation of the body 24 with the base 18 upon the members 52 and 53 where the greatest frictional movement occurs. The members 52 and 53 also prevent the relatively concentrated stress in these areas from concentrating the strain on the base in such limited areas as would be likely to cause rupture of the said base.

Similar action takes place in the back portion 56 of the chair 10 with the exception that the 10 stresses are usually of lower order and the distortion or movement of the parts occurs to a correspondingly lesser degree. As seen in Figure 2 the central part of the body portion 74 lies rearwardly of the back base 68 and disposed rearwardly of this is the rear sheet of upholstery material 84. For the purpose of clarity in the drawings the thickness of the sections of the planar material has been exaggerated. In a finished article the rear upholstery surface 84 would present a substantially smooth appearance.

Turning now to the second embodiment of the invention illustrated in Figures 8 and 9 for the purpose of avoiding needless repetition parts corresponding to the first embodiment of the invention are given the same reference character with the addition of the numeral "1" as a prefix.

The principal difference existing between the second embodiment of the invention and the first embodiment of the invention lies in the spring enclosing portion 128 wherein the same is completely closed with the exception of the orifices through which the flexible frame attaching element 141 passes. This enclosing of the spring 136 within the bight 128 may be accomplished by the 30 row of stitches 185 and the chamber 186 may be provided with a lubricant, if desired. Such lubricant may have any desired characteristics and, for example, may be composed of a mixture of 35 wax and graphite, which is applied to the convolutions of the spring 136. It may be noted in connection with the second embodiment that the enclosing of the spring 136 prevents the entrance of dust and dirt into the chamber 186 and thereby promotes the unaffected operation of the 40 spring 136.

The principal frame attaching elements 41 and 45 141 may be composed of rope of the vegetable fibre type such as manila, cotton or linen, or where desired the same may be composed of steel cable. In order to promote the smooth and noiseless operation of the device the cable or rope forming the flexible frame attaching elements 41 or 141 may be suitably impregnated with a lubricant such as wax.

It may be noted that downward pressure upon the central area of the body portion 24 of the element 23 (or 73, or 123) causes a flattening of the bight 28 and the other bight portions corresponding thereto. This in turn causes the inner opposed surfaces of the elongated strap element 24 to approach each other and in doing so they bear against the diametrically opposite portions of the convolutions of the spring 36 or the other 50 springs corresponding thereto. Such pressure upon said convolutions causes a frictional engagement which has a snubbing or shock absorbing effect. Thus when a sitter's weight is suddenly placed upon the seating portion 57 or the back portion 56, by transmission of the gravitational forces as previously described, tension is placed upon the units 23, or 73, or the other units corresponding thereto, and this causes pressure within the bight or spring enclosing portion 28 or other portion corresponding thereto, which re-

duces the speed of contraction of the spring 36, or other springs corresponding thereto.

It will be noted that the unit 23 or 13, or other unit corresponding thereto is substantially flexible throughout the area which is adapted to support the respective base elements, such as the base 18, or the base 68, so that the comfort providing qualities of the upholstered article 10 are enhanced.

Where certain filling materials are used, as for example, foam rubber, it may be desirable to eliminate the covering element 20 or the covering element 10, as well as the resilient elements 19 or 69, and to have the cushioning element 21 or 71 extend into the chamber normally occupied by the resilient elements 19 or 69. In such construction weight caused by the sitter is transmitted through the thus enlarged cushioning elements directly to the bases which in turn receive controlled resilient support by the support units 23 or 13.

It may be noted that in connection with the present disclosure the units 23 have been described as having springs corresponding to the spring 36 at both of the ends thereof. Where desired for purposes of obtaining either a less expensive construction or an altered seating action the spring corresponding to the spring 36 may be omitted at one of the ends of the unit 23 with a corresponding loss of the function of said spring.

It may thus be seen that I have provided a novel and useful upholstery construction which may be readily fabricated in large quantities at low cost and which provides a high degree of comfort, utility and durability. Chairs or other upholstered articles constructed in accordance with my invention are not only comfortable in use but have a shock absorbing action when sudden loads are placed upon them with a consequent reduction in undue strain in the parts, a feature which provides for lengthened satisfactory life of the article of furniture.

I wish it to be understood that I do not desire to be limited to the exact details of construction shown and described, for obvious modifications will occur to a person skilled in the art.

I claim:

1. Furniture construction for use by an occupant, comprising: a frame; a platform connected to said frame; a flexible base connected to said frame; load transmitting means disposed between said platform and said base; a support unit including a flexible body having an orifice of predetermined size; said base resting on said flexible body; a compressible spring larger than said orifice so as to be incapable of passing through the orifice, said spring having inner and outer portions and being engaged at the outer portion thereof with said flexible body at said orifice; an elongated frame attaching element connected at one end thereof to said frame; said frame attaching element at a portion thereof which is spaced from its said end penetrating said orifice in the flexible body and penetrating said spring and engaging inner portions of said spring; and means to prevent disconnection of said spaced portion of the frame attaching element from said inner portions of the spring; whereby the weight of the occupant on the platform is transmitted to the base which is moved downwardly causing the flexible body which carries said base to move away from the frame, the frame attaching element having a restraining action on said spring and thereby causing a compression of said spring against said flexible body.

2. Furniture construction for use by an occu-

pant, said construction comprising: a frame; a platform connected to said frame; a flexible base connected to said frame; load transmitting means disposed between said platform and said base; a support unit including a flexible body having an orifice of predetermined size; said base resting on said body; a helical coil compression spring larger than said orifice and engaged at an outer portion thereof against said flexible body at said orifice; an elongated frame attaching element connected at one end thereof to said frame; said frame attaching element at a portion thereof which is spaced from its said end penetrating said orifice and penetrating said spring substantially axially thereof and engaging inner portions of said spring; means to prevent the attaching element from pulling completely out of said spring; whereby weight of the occupant on the platform is transmitted to the base which is moved downwardly causing the flexible body which carries said base to move away from the frame, the frame attaching element having a restraining action on said spring and thereby causing a compression of said spring against said flexible body.

3. Furniture construction for use by an occupant, comprising: a frame; a platform connected to said frame; a flexible base connected to said frame; load transmitting means disposed between said platform and said base; a support unit including a flexible body having an orifice of certain size; said base resting on said body; a U-shaped compression spring engaged at an end thereof by said flexible body at said orifice; an elongated flexible frame attaching element connected at an outer end thereof to said frame; said flexible frame attaching element penetrating said orifice and axially penetrating said spring; means anchoring said attaching element to inner portions of said spring; whereby the weight of the occupant on the platform is transmitted to the base which is moved downwardly causing the flexible body to move away from the frame, the frame attaching element having a restraining action on said spring and thereby causing an axial compression of said spring along the frame attaching element and against said flexible body.

4. In furniture construction for use by an occupant, said construction having a frame and a flexible base attached to said frame and which carries the weight of the occupant; a base supporting unit comprising: a strap element extendable beneath said base for carrying said base to support the same, said strap element having an enclosure with an outer end; an elongated frame attaching element; a compressible spring encased within said enclosure and having a first portion thereof in engagement with the outer end of said enclosure and having a second portion; said frame attaching element having a first portion connectible with said frame and a second portion penetrating a second portion of said spring, which second portion is spaced along said strap element a substantial distance from the outer end of the enclosure; means for engaging said attaching element with said spring second portion; whereby when installed in an article of furniture, weight upon the base causes a movement of the strap element away from the frame and a compression of the spring, the second portion of which is restrained in movement away from the frame by the frame attaching element.

5. In furniture construction, for use by an

occupant, said construction having a frame and a flexible base attached to said frame and which carries the weight of the occupant; a base supporting unit comprising: a flexible strap element extendable beneath said base for carrying said base to support the same, said strap element being folded upon and connected to itself to form an enclosure; an elongated flexible frame attaching element; a compressible spring disposed within said enclosure and having a first portion thereof in engagement with the outer end of said enclosure; said frame attaching element having a first portion connectible to said frame and penetrating said enclosure and a second portion penetrating said spring in an axial direction and engaging with a second portion of said spring, which spring second portion is spaced along said strap element a substantial distance from the outer portion of said enclosure; whereby as installed, the base causes a movement of the strap element away from the frame and a compression of the spring, the second portion of which is restrained in movement away from the frame by the frame attaching element.

6. In furniture construction for use by an occupant, said construction having a frame and a flexible base attached to said frame and which carries the weight of the occupant; a base supporting unit comprising: a flexible strap element for extension beneath said base for carrying said base to support same, said strap element being folded upon itself to form a loop, the folded portion of the strap element which forms the loop being secured at its end to the body of the strap; a frame attaching element in the form of a flexible elongated member; a U-shaped compression spring confined within said loop and having its free ends in engagement therewith; said frame attaching element slidably penetrating said loop and extending through said spring, the ends of the said attaching element being adapted to be secured to said frame; whereby when installed, weight upon the base causes a movement of the loop away from the frame and this compresses the spring against the restraining action of the frame attaching element.

7. A device as claimed in claim 6 in which the spring is of helical coil construction.

8. A device as claimed in claim 6 in which the ends of the frame attaching element are permanently connected outwardly of the loop of the strap element.

9. An auxiliary elastic support for use in furniture seat construction or the like comprising a seat frame and a flexible base in the nature of a spring supporting web attached thereto; said auxiliary support comprising a body element to carry said base, said body element having an orifice; a compression spring, a first portion of which engages said body element near said orifice, said orifice being smaller in diameter than

the size of said spring whereby said spring may not penetrate said orifice; an elongated frame connecting element passing through said orifice in a slidable manner and axially penetrating said spring to engage a second portion of said spring, said second spring portion being located inwardly on said body element and spaced from said orifice; and means to prevent the withdrawal of said frame connecting element from said spring.

10. An auxiliary elastic support for use in furniture construction or the like comprising a seat frame and a base in the nature of a spring supporting web attached thereto; a body element in the form of a flexible strap for extension beneath said base, an end of which is folded upon itself and secured to an inner portion of itself to form a closed bight; said body element being adapted to carry said base and having a pair of orifices located in said bight the edges of said orifices being reinforced; an elongated helical coil compression spring located within said folded portion and with the ends thereof engaging the bight at the orifices said spring having pressure distributing members in the ends thereof; an elongated flexible frame connecting element passing through said orifices, pressure distributing members and spring and forming the spring into substantially U-shape; the exposed portions of the frame connecting element being interconnected outwardly of said bight and adapted to be secured to said frame; and means at the other end of said strap for securing the same to said frame whereby when applied to a base and a seat frame, longitudinal tension and downward pressure upon the body element by the base will cause a flattening of the bight and increased friction on lateral surfaces of said spring to produce a spring controlling or snubbing effect.
